(57) **CLAIM**

The ornamental design for a head for powered tongue jack, as shown and described.

DESCRIPTION

FIG. 1 is a perspective view of a head for powered tongue jack showing our new design;

FIG. 2 is a side elevation view thereof;

FIG. 3 is a perspective view thereof;

FIG. 4 is a rear elevation view thereof;

FIG. 5 is a perspective view thereof;

FIG. 6 is a side elevation view thereof;

FIG. 7 is a perspective view thereof;

FIG. 8 is a front elevation view thereof;

FIG. 9 is a top plan view thereof; and,

FIG. 10 is a bottom plan view thereof.

In the drawings, the broken lines depict portions of the

article that form no part of the claimed design.
